UNITED STATES PATENT OFFICE.

OSWALD SCHLAUPITZ, OF CANTON, OHIO, ASSIGNOR TO THE TIMKEN ROLLER BEARING COMPANY, OF CANTON, OHIO, A CORPORATION OF OHIO.

GAUGING MACHINE.

Application filed August 9, 1923. Serial No. 656,492.

To all whom it may concern:

Be it known that I, OSWALD SCHLAUPITZ, a citizen of the United States, and a resident of the city of Canton, county of Stark, and 5 State of Ohio, have invented a certain new and useful Improvement in Gauging Machines, of which the following is a specification.

My invention relates to gauging machines 10 and has for its principal object a machine in which a roller for roller bearings and the like can be gauged at one setting for size, taper and circularity. The invention consists principally in providing a gauging machine with spaced gauging means, said 15 means having members contacting with a roller at spaced points on the bearing surface thereof, whereby the size of the roller is gauged, the taper thereof is indicated by the relative positions of the pointers of the 20 two gauging means, and the roller is shown to be round or out-of-round depending upon whether the pointers are stationary as the roller is rotated under the contact members 25 or whether the pointers move. The invention further consists in the gauging machine and in the parts and combinations of parts hereinafter described and claimed.

In the drawings which form part of this 30 specification and wherein like reference characters indicate like parts wherever they occur,

Fig. 1 is a side elevation of a gauging machine embodying my invention;

Fig. 2 is a vertical sectional view on the 35 line 2-2 in Fig. 1;

Fig. 3 is a detail view showing the roller holding and rotating mechanism;

Fig. 4 is a detail view showing the means 40 for rotating the roller while it is held in the gauging machine;

Fig. 5 is a sectional view on the line 5-5 of Fig. 1;

Fig. 6 is a sectional view on the line 6-6 45 of Fig. 1;

Fig. 7 is a sectional view on the line 7-7 of Fig. 1 and Fig. 8 is a detail sectional view taken at right angles to section 5-5.

A housing 1 is mounted on a suitable base 50 2. Projecting from the lower front of the housing are spaced ring-shaped lugs 3 that are inclined from the vertical. Slidably mounted in alining holes in said lugs is a hollow rod 4 to which is secured a longitudi-

nally extending key 5 that fits in a key- 55 way 6 in the lower lug. The middle portion 7 of said hollow rod is threaded and a threaded nut 8 is mounted thereon between the lugs. The hollow rod 4 is moved in the lugs by turning the adjusting nut 8. Secured to the upper end of the hollow rod 4 is a recessed member 9 constituting a seat for a block 10 that is adapted to hold the roller 11 being gauged. The seat 9 is prevented from turning on the hollow rod 4 by 60 means of pins 12 fitting in holes in the seat and rod and is held on the rod by means of a threaded bolt 13, a washer 14 that closes the lower end of the hollow rod and a nut 15 that bears against said washer. Fitting 70 in a suitable recess in the lower lug 3 is a spring 16 that bears against the washer 14, such spring serving to take up any looseness between the hollow rod and its adjusting nut 8.

The block 10 is held in position on the seat 9 by suitable screws 17. The block 10 may be removed from the seat and replaced with a different block, and thus the same machine may be used for gauging rollers of 80 different kinds and sizes.

The block is provided with an upstanding portion 18 constituting a bearing for the side of a roller 11 being gauged. The bottom of the block is inclined so that the upper 85 edge of a roller lying in the block is horizontal if the roller is of standard taper. Mounted in the block 10 and in the upstanding portion 18 thereof are diamond pointed pins 19, whereby the roller is supported at 90 the sides and at the large end so as to be easily rotated and whereby it is accurately positioned and held.

Pivotedly mounted on the upper lug 3 as 95 by a pin 20 is a lever 21 and a bearing member 22 is mounted so as to project above said lever 21. Rotatably mounted in the bearing member 22 is a spindle 23 that is provided at one end with a pulley 24 by means of which it may be rotated. Secured to the 100 spindle 23 as by means of flanges 25 thereon is a drive roll 26 of rubber or other suitable material, that is adapted to bear against a roller 11 in the machine and rotate it while it is being gauged. The lever 21 may 105 be raised so as to cause the drive roll 26 to engage a roller 11 in the machine, and it may be lowered so as to pull the drive

roll 26 away from the roller 11 so as to permit it to be removed from the machine and another roll to be inserted to be gauged. Mounted on the upper lug 3 is a stop finger 5 27 that limits the downward travel of the lever.

The drive roll 26 is constantly rotated by means of a belt 28 that passes thereover. Secured to the base 2 underneath the spin- 10idle pulley 24 is a support 29 in which is mounted an idler pulley 30 over which the belt 28 runs. Also mounted on the base 2 is a bracket 31 to which is secured a pulley 32 over which said belt 28 runs. Said pul- 15ley 32 is mounted on a shaft 33 that is constantly rotated in any manner, as by the drive belt 34 and pulley 35 shown in Fig. 1.

Mounted in the housing 1 are counterpart 20 gauging mechanisms each of which is provided with a contact lever 36 that is rotatably mounted on a shaft 37 in the housing. The contact levers 36 are spaced apart so as to make contact with a roller 11 near the ends thereof. Beneath the shaft 37 on which the 25 contact levers 36 are mounted is a screw 38 which is provided on one side of its middle with a righthand thread and on the other side a lefthand thread. The ends of the screw 38 extend through the housing 30 and are provided with suitable bushings 39. One end of the screw 38 is provided with a knob 40 by which the screw may be turned. The other end 41 of the screw 38 is split and provided with a tapped hole 35 in which is screwed a lock screw 42 that is provided with a suitable knob 43 for turning it. When the lock screw 42 is screwed tight into the adjusting screw 38 it expands the end of the screw in its bearing 39 and 40 locks the adjusting screw against rotation. On each threaded portion of the adjusting screw 38 is a threaded ring 44 that has upwardly projecting yoke arms 45 that engage a shouldered ring 46 on one of the 45 contact levers. Thus, by loosening the adjusting screw 38 and then turning it, the contact levers 36 may be brought together or moved apart, thereby adjusting the gauging mechanism for any desired length of roller.

The end of each contact lever 36 projects through a slot in the housing and terminates above the roll block 10. Mounted on the underside of each lever 36 is a strip 47, pref- 55 erably of spring metal in the forward end of which is mounted a diamond 48 for making contact with a roller. Each diamond holder strip 47 is secured to its lever 36 by a screw 49 and the end of the diamond holder may be moved away from the lever. A pin 50 is secured to each diamond holder 60 47 and rests in a hole 51 in the contact lever 36, thus properly positioning the holder with respect to the lever. Threaded 65 into the end of each contact lever 36 and

bearing against the diamond holder 47 is a screw 52 by means of which the end of the diamond holder may be forced away from the end of the contact lever to properly position it. By this means the herein- 70 after described indicating pointer may be adjusted. Secured to the lower part of each threaded ring 44 and the end of the corresponding contact lever 36 is a light spring 53 that tends to prevent the contact lever 75 from falling down too far when the roller that has been gauged is removed from the machine.

A toe 54 at the rear end of each contact lever 36 bears against a projecting portion 80 55 of a lever 56 that is pivotally mounted on a shaft 57 in the housing. The ends of the shaft are mounted in bushings 57^a in the side walls of the housing. Said projecting portion 55 is wide enough so that 85 the contact levers 36 may maintain contact therewith in all of their positions. Pivotally secured to a shoulder on each lever 56 is a segment gear 59 that has a flat spring 60 secured thereto. On the lower part of 90 each lever 56 is a pin 61 that rides between the segment gear 59 and the spring 60. The spring 60 is strong enough to normally hold the pin 61 against the segment gear so that the two move together, but in case of mis- 95 handling the machine the spring 60 yields and prevents the gauging mechanism from being damaged.

Secured to each pin 61 and to the rear 100 wall of the housing 1 is a spring 62 that tends to return the gauging mechanism to its original position after the gauging operation.

Each segment gear 59 meshes with a 105 pinion 63 that is secured on a shaft 64 in the housing. The outer end of each shaft 64 is mounted in a bushing 64^a in the side wall of the housing. Mounted on the hub of each pinion 63 is an arm 65 to which is secured a segment gear 66 that meshes with 110 a pinion 67 on a shaft 68 in the upper part of the housing. Secured to each pinion 67 is a pointer 69 that moves in an arcuate slot 70 in the front of the housing. Along an edge of each slot 70 is a graduated scale 71 along which each pointer moves. Each 115 pinion 67 is provided with a counterweight 72 to counterbalance the weight of its pointer.

The housing is provided with a central 120 brace member 73 between the two gauging mechanisms and said brace contains bearings 74 for the several shafts that pass therethrough, the outer bearings being supported in the housing walls as hereinbefore described.

The operation of the machine is as follows:

A gauging block 10 of the proper dimensions for the kind of rollers 11 to be gauged 130

is placed in position on the seat 9. A master roller of exactly standard shape and dimensions is placed on the supporting pins 19 of the gauging block 10 under the contact 5 points 48 of the contact lever 36. The hollow rod 4 is then raised or lowered by turning the nut 8 until one of the pointers 69 registers with zero on the scale 71. The other pointer is then adjusted by turning the 10 adjusting screw 52 of the contact lever 36 until said pointer also registers with zero on its scale 71. The contact levers 36 are adjusted by means of the adjusting screw 38 so that the contact points 48 are near the 15 ends of the roller 11. After the above adjustments the machine is ready for gauging.

The drive roll 26 is constantly rotated as above described. By pulling down on the lever 21 the drive roll is moved away from 20 the gauging block 10 and a roller 11 is placed thereon in position to be gauged. The lever 21 is then raised until the drive roll 26 contacts with and rotates the roller 11. The position of the pointers 69 along the scales 25 71 shows the size of the roller. The position of the pointers 69 with respect to each other shows the taper. If the roller is of the proper taper, the pointers 69 will be opposite each other (that is, pointing to the 30 same graduation on the scale); whereas if the roller is off-taper, the pointers will be spread apart, the distance of the spreading showing the amount that the roller is off-taper, and the direction in which the roller 35 is off-taper depending upon which pointer is above the other. As the roller 11 is rotated, the pointers 69 will move back and forth along the scale if the roller is out-of-round; whereas they will remain stationary 40 if the roller is truly circular.

The gauging machine herein described has numerous advantages. It enables rollers to be gauged for size, taper and out-of-roundness at one handling and one setting, instead of requiring a separate gauging for each of said items. The machine is adapted for use with rollers of various sizes on account of the fact that the gauging block is removable.

Obviously, numerous changes may be made without departing from the invention and I do not wish to be limited to the precise construction shown.

What I claim is:

1. A machine for gauging rollers comprising a support for a roller, means for rotating a roller on said support, a pair of spaced independent contact levers, means for supporting said levers relatively to said support for engaging the roller, separate indicating pointers, means for operatively connecting one of said pointers with one of said contact levers and means for operatively connecting the other of said pointers with

2. A machine for gauging rollers comprising a support for a roller, means for rotating a roller on said support, a pair of spaced independent contact levers, means for supporting said levers relatively to said support 70 for engaging the roller, separate indicating pointers, means for operatively connecting one of said pointers with one of said contact levers, means for operatively connecting the other of said pointers with the other of said contact levers, and means for moving said contact levers toward and away from each other.

3. A machine for gauging rollers comprising a support for a roller, a continuously 80 rotating drive roll, means for moving said drive roll into engagement with said roller to rotate it, a pair of spaced independent contact levers, means for supporting said levers relatively to said support for engaging the roller, separate indicating pointers, means for operatively connecting one of said pointers with one of said contact levers and means for operatively connecting the other of said pointers with the other of said contact levers. 85

4. A machine for gauging conical rollers comprising a support for a roller to be gauged, means for rotating a roll on said support, a pair of spaced independent contact levers engaging said roller near its ends, means for supporting said levers relatively to said support, a pair of independent indicating pointers and means operatively connecting said contact levers and said pointers, 90 whereby said pointers are operated respectively by said contact levers. 95

5. A machine for gauging conical rollers comprising a support for a roller to be gauged, said support being arranged so that the upper edge of a roller of standard taper thereon is horizontal, a pair of spaced independent contact levers engaging the upper edge of said roller near its ends, means for supporting said levers relatively to said support, a pair of independent indicating pointers and means operatively connecting said contact levers and said pointers, whereby said pointers are operated respectively by 100 said contact levers. 105

6. A machine for gauging conical rollers comprising a support for a roller to be gauged, said support being arranged so that the upper edge of a roller of standard taper thereon is horizontal, means for rotating said roller, a pair of spaced independent contact levers engaging the upper edge of said roller near its ends, means for supporting said levers relatively to said support, a pair of independent indicating pointers and means operatively connecting said contact levers and said pointers, whereby said pointers are operated respectively by 110 said contact levers, and a graduated scale 115 along which said pointers move, said point- 120

ers being set to point to zero when a roller of standard size and taper is gauged, whereby the position of the pointers along the scale indicates the size of the rollers, the position of the pointers relative to each other indicates whether the rollers are of the proper taper, and the oscillating of the pointers indicates that the rollers are out of round, the pointers remaining stationary if the roller is round at both ends.

7. A machine for gauging rollers comprising a support for a roller, a shaft, a pair of spaced independent contact levers slidably and rotatably mounted on said shaft, means for supporting said levers relatively to said support, a screw threaded member having a right hand threaded portion and a left hand threaded portion a member on said right hand threaded portion having a portion engaging the hub portion of one of said contact levers and a similar member on said left hand threaded

portion having a portion engaging the hub portion of the other contact lever.

8. A machine for gauging rollers comprising a support for a roller, a shaft, means for supporting said shaft relatively to said support, a pair of spaced independent contact levers slidably and rotatably mounted on said shaft, means for supporting said levers relatively to said support, a screw threaded member having a right hand threaded portion and a left hand threaded portion a member on said right hand threaded portion having a portion engaging the hub portion of one of said contact levers and a similar member on said left hand threaded portion having a portion engaging the hub portion of the other contact lever, and means for locking said threaded member against rotation.

Signed at Canton, Ohio, this 4 day of August, 1923.

OSWALD SCHLAUPITZ.
